FIG. 1 is a top perspective view of a coat rack, showing my new design;
FIG. 2 is a bottom perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof; and,
FIG. 9 is a partial enlargement of FIG. 1.

The broken lines in the drawings illustrate the portions of the coat rack, which form no part of the claimed design.
